UNITED STATES PATENT OFFICE.

LORON O. BURNHAM, OF FRANKFORT, MICHIGAN.

MOLD FOR BUILDING-BLOCKS.

SPECIFICATION forming part of Letters Patent No. 760,678, dated May 24, 1904.

Application filed October 31, 1903. Serial No. 179,317. (No model.)

To all whom it may concern:

Be it known that I, LORON O. BURNHAM, a citizen of the United States, residing at Frankfort, in the county of Benzie and State of Michigan, have invented certain new and useful Improvements in Molds for Building-Blocks; and I do hereby declare that the following is a full, clear, and exact description of the invention, such as will enable others skilled in the art to 10 which it appertains to make and use the same.

My invention relates to molds for manufacturing building-blocks from plastic material; and it consists of certain novel features of combination and construction of parts, as 15 will be hereinafter clearly set forth, and pointed out in the claim.

The prime object of my invention, among others, is to provide a mold of the character specified by means of which building-blocks 20 of various shapes and sizes may be formed to meet all of the conditions in erecting a building or culvert or bridge and similar work whereby the building-block will be found ready to accommodate itself to various positions where it may be placed.

Other objects and advantages will be hereinafter made clearly apparent, reference being had to the accompanying drawings, which are made a part of this application, and in 30 which—

Figure 1 shows a perspective view of my mold complete ready for use. Fig. 2 is a central section of Fig. 1 on line 2 2. Fig. 3 is a transverse section of Fig. 1 on line 3 3. Fig. 35 4 is a perspective view showing a slight addition to the mold as illustrated in Fig. 1. Fig. 5 is a similar view to that presented in Fig. 1, showing additional attachments to be employed in connection therewith. Figs. 6, 7, 40 8, 9, and 10 show various sizes and shapes of building-blocks as may be produced from my mold. Fig. 11 is a perspective view showing one end of my mold and indicating the position of certain corner-pieces by dotted lines. 45 Fig. 12 shows a form of blocks produced by the mold and the attachments illustrated in Fig. 4.

The various details of my invention and coöperating accessories will for convenience 50 be referred to by numerals, the same numeral

applying to a similar part throughout the several views, and, referring to the numerals on the drawings, 1 and 2 indicate side sections of my improved mold, while 3 and 4 show the end sections thereof, and 5 designates a frame-section to which said side and end sections are pivotally secured, as by suitable hinges 6.

It will be observed by reference to Figs. 1 and 3 that the inner face of the side wall 2 is properly formed, so as to produce a block of 60 the pattern styled "rock-faced," this being readily accomplished by hollowing out and roughening the inner surface of the side wall 2, as indicated by the numeral 7 is Fig. 3 and other views.

To each end section 3 and 4 I attach or integrally form therewith the vertically-disposed rib-like member 8, one for each end section, said rib being disposed in the middle portion of the mold and is designed to form 70 in the end of the building-block an opening or recess whereby when two building-blocks are joined together end to end a hollow space or air-chamber will be formed in the wall, as is desirable in this variety of construction. 75

The rib-sections 8 are shown to be integrally formed with the end sections 3 and 4 in Fig. 2. It is also desirable that the central portion of each building-block shall be provided with an opening extending entirely through 80 the same, as indicated by the numeral 9, whereby when the building-blocks are placed one above the other, as in building a continuous communicating chamber is formed by staggering the position of the openings 9 with the 85 end recesses formed in the end of each block by means of the end sections 8, as hereinbefore stated, said end recesses being indicated by the numeral 10.

It is obvious that the end recesses may be 90 any preferred shape or size and may be formed in one or both ends of each building-block, as preferred.

In Fig. 8 it will be seen that a corner building-block is provided, inasmuch as the rock-face (indicated by the numeral 11) is extended along one side and across one end of the building-block, thereby fitting it for use upon the corner of the wall. I also provide a number 95 of attachments for my improved mold, one of 100

- which is located in the central part of the mold-box and consists of the side walls 12, which are carried by the floor-section 13, said walls being of sufficient extent to reach upward to the top of the frame-section 5, whereby when the plastic material is placed in the mold-box and pressed down therein the upper surface of such material will be left flush with the frame-section 5 and the upper edges 5 of the walls 12, thereby forming a hollow opening entirely through the block thus formed. I also provide the lid-section 14, adapted to be easily taken out of its position between the walls 12, the object of said lid being to prevent 15 the material from falling between said walls. I also provide for co-operation with the walls 12 the end sections 15, which are pivotally mounted upon the rods 16, extending transversely across from one wall 12 to the other. 20 Each of the end sections is provided at its lower end with a lug or extension 17, which is provided upon its outer end with a beveled extension or terminal 18, and as said extension 17 is adapted to reach down through a recess 19 25 in the bottom section 13 it will be understood that the lower ends of the end members 15 will be held in a vertical position. In order that the entire box thus or otherwise constructed and comprising the side walls 12 and end sections 30 15 may be bodily removed or lifted from out the mold-box, I provide suitable locking mechanism for holding the end walls 15 in a vertical position, whereby the extensions 18 will be brought against the beveled ends of the recesses 19, said locking device consisting in this instance of the arms 20, hinged together at their inner ends, as indicated by the numeral 21, and pivotally connected at their outer ends to the ears 22, carried by each end section 15. It therefore follows that by raising the hinged joint 21 upward the lower ends of the end sections 15 will be drawn toward each other sufficiently to disengage the extension 17 from the recesses 19, and thereby permit the core to be easily 45 moved downward, and thereby leave the opening formed by the walls 12 and said end sections free and unobstructed.
- In some instances each end section 15 may be provided upon its outer side with a transverse rib 23 in order that a more desirable building-block may be produced.
- In Fig. 4 I have shown the addition of a block 24, located alongside of the rib-section 8, and it therefore follows that this corner of the 55 building-block will not be of as great extent as the opposite corner, or that corner formed upon the opposite side of the rib 8. In thus reducing the size or extension of one corner of the building-block I form it ready to fit 60 around one of the joist or sleepers or to accommodate a studding, said open space being indicated by the numeral 25 in Fig. 12. When it becomes desirable to shape the block to be produced so that it will accommodate itself to

fit around one of the obliquely-disposed rafters 65 supporting the roof, I then employ a triangular block 26, the result being that that form of block, as indicated in Figs. 9 and 10, will be produced, the position of the triangular block and the size or extent thereof determining a corresponding shape for the block formed. 70

It becomes desirable that a convenient and easily-operated means shall be provided for locking the lower or free edges of the side and end walls in operative union with each other, and I therefore provide for each of the side walls a spring-like hook 27, having its hook face or side turned inward to engage the contiguous edge of the end walls, and in order to 75 hold the end and side walls against all relative movement I also provide the locking-bail 28, having upon each end an angular extension 29, shaped to engage a contiguous part of the ends of the side walls, one of said extensions being 80 bent outward to provide the controlling-handle 30, or both of said extensions may be provided with such a handle, if desired. It therefore follows that by swinging the handle outward the members 29 will be brought out of engagement with the side walls, thereby permitting the side and end walls to be moved freely outward at their lower edges, whereby the mold-box may be lifted off of the bottom section, leaving the molded block formed within the 95 mold-box resting upon the bottom section ready to be carried away for storage after it has become set.

It will thus be seen that I have provided reliably-efficient means which while simple in 100 character will produce a building-block of almost any desired shape and will form the sides of the building-block with rock-faces, or both sides and each end may also be so configured or shaped, if preferred. It will be 105 furthermore obvious that the building-block may be properly shaped to accommodate itself when placed in the wall to fit around a contiguous joist or sleeper or a rafter supporting the roof, and while I have described the preferred construction deemed necessary in carrying out my invention I wish to comprehend in this application all substantial equivalents and substitutes.

Having thus fully described the construction of my invention, it is thought that the use or operation thereof will be made clearly apparent, though it may be stated that after the mold-box has been formed and the parts thereof assembled substantially in the manner shown in Fig. 1 the plastic material is placed therein and properly tamped or pressed downward and afterward brought flush with the upper surface of the frame-section 5, and after the plastic material shall have become sufficiently hardened the lid or closure-section 14 may be removed and the hinged joint 21 drawn upward, as by the fingers of the operator, which 110 115 120 125

- will incidentally draw the lower ends of the end sections 15 into a position to disengage the extensions 17 from the recesses 19, thereby permitting the central core comprising the 5 walls 12 in said end sections 15 to be bodily lifted from the opening which it has formed in the building-block, it being understood that the lower ends of the end sections 15 shall be narrower than the upper ends thereof, thereby 10 insuring that the central opening in the building-block will be slightly conical in shape and enabling the central core-box to be more easily removed than if the wall-sections 12 were truly vertical or parallel with each 15 other.
- If it should be desirable to form one edge of the building-block so that it will be of less extent than the opposite corner, so as to fit around a joist or the like, then I place the 20 block 24 in the position shown in Fig. 4 and the operation repeated, the result being that the block when produced will be of less size upon one side than upon the other, as set forth in Fig. 12.
- 25 Believing that the advantages and construction and manner of using my improved core-box for building-blocks have thus been made clearly apparent, further description is deemed unnecessary.

What I claim as new, and desire to secure 30 by Letters Patent, is—

The herein-described core-box adapted to form a building-block of any desired size and shape, comprising a suitable frame 5; side and end walls properly connected to said frame and left free at their lower ends; a bottom section 13 coöperating with said end and side walls and having a pair of longitudinal recesses 19; a removable core coöperating with the core-box and comprising the side 40 walls 12 and end sections 15; means to operatively connect said parts together whereby they may be freely removed from the plastic core formed around the same; removable devices as indicated by the numerals 24 and 26 45 adapted to shape the corners of the building-block as desired and additional means to lock the free edges of the end and side walls in coöperative relationship, all combined substantially as specified and for the purpose set 50 forth.

In testimony whereof I affix my signature in the presence of two witnesses.

LORON O. BURNHAM.
